UNITED STATES PATENT OFFICE.

HENRY WILLIAM HOLLAND AND WILLIAM MANSFIELD, OF LONDON, ENGLAND,
ASSIGNORS TO HOLLAND AND HOLLAND, LIMITED.

SIGHT FOR SMALL-ARMS.

1,073,491.

Specification of Letters Patent. Patented Sept. 16, 1913.

Application filed June 23, 1913. Serial No. 775,409.

To all whom it may concern:

Be it known that we, HENRY WILLIAM HOLLAND and WILLIAM MANSFIELD, subjects of the King of Great Britain, both residing at 98 New Bond street, London, England, have invented new and useful Improvements in and Relating to Sights for Small-Arms, of which the following is a specification.

10 This invention relates to bolt small arms having a safety device free to turn about a longitudinal axis.

According to this invention the thumb piece of the safety device is adapted for use 15 as, or to carry, a sight and the mechanism of the small arm is modified in such a manner as to allow it to be fired when the safety device is in a vertical position.

Figures 1 to 6 illustrate the application 20 of the invention to a Mauser rifle, and Figs. 7 to 15 illustrate the application of the invention to a Mannlicher rifle.

Fig. 1 is a side elevation and Fig. 2 a rear elevation showing the safety device, the 25 rear portion of the bolt and other parts of a Mauser rifle. Fig. 3 is a detached front elevation of the safety device. Fig. 4 is a side elevation of the rear portion of the striker which carries the firing pin. Figs. 30 5 and 6 are diagrammatic rear elevations omitting the striker and showing the safety device in different positions. Figs. 7 and 8 are sectional side elevations and Fig. 9 is a rear elevation showing the safety device, the 35 rear portion of the bolt and other parts of a Mannlicher rifle. Figs. 10 and 11 are detached front and rear elevations of the safety device. Fig. 12 is a front elevation of the nut on the rear end of the striker. 40 Fig. 13 is a diagrammatic section on the line 13—13, Fig. 7, and Figs. 14 and 15 are similar views showing the parts in different positions.

In Figs. 1 to 6, *a* is the safety device, *b* 45 is the bolt, *c* is the lever fixed to the bolt and *d* the bearing carrying the bolt. The safety device *a* is carried by a spindle *e* (shown in dotted lines in Fig. 1 and full lines in Fig. 3) which is free to turn in a 50 hole in the bearing *d* and it has fixed to it a disk *f* having a notch *g* cut in it. When the safety device is in the position shown at Fig. 5 the disk *f* lies in the path of the shoulder of the striker *h* so that the striker 55 cannot move from the cocked position

(shown in dotted lines in Fig. 1) to the fired position (shown in full lines) and the rifle cannot be fired but when the safety device is in the position shown at Fig. 6 the shoulder can pass through the notch *g* 60 and fire the rifle. All the above is well known and requires no further description for it forms no part of the present invention.

According to this invention a second 65 notch *j* is cut in the disk *f* and the safety device *a* is adapted to form, or carry, a sight. In the arrangement shown *k* is an aperture or peep sight carried by a stem *l* free to move up and down in guides in 70 the safety device *a* and having upon it a rack *m* gearing with a nut *n* free to turn in bearings in the safety device *a*. *o* is a spring carried by the safety device and tending to force its hook *p* against the 75 flange *q* of the bearing *d* and thus retain the safety device and sight by friction in any position.

In Figs. 7 to 15 *a* is the safety device, *b* is the bolt, *c* is the lever fixed to the bolt and 80 *e* is the spindle carrying the safety device which in this case works in a hole in the sleeve *r* which is secured to the striker *h* by the nut *s*. When the parts are in the positions shown at Figs. 8 and 15 the front end 85 of the spindle *e* enters a notch *t* in the rear end of the bolt *b* and prevents the striker from moving forward and firing the rifle but the end of the spindle is cut away at *u* 90 so that when the parts are in the position shown at Fig. 14 the striker is free to move forward and fire the rifle. The safety device *a* is forced rearward by a spring *v* 95 which causes a swelling *w* to engage with the edge of the nut *s* and thus hold the safety device in the positions shown at Figs. 14 and 15. All the above is well known and requires no further description for it forms no part of the present invention.

According to this invention the spindle *e* 100 is cut away at *x* as well as at *u* so that the rifle can not only be fired when the parts are in the position shown at Fig. 14 but also when they are in the position shown at Figs. 7 and 13 and the nut *s* is notched at *y* to receive the swelling *w* on the safety device 105 and thus hold the latter in the position shown at Figs. 7 and 13. The safety device also is adapted to form or carry a sight, the arrangement shown being the same as Figs. 110

1 to 6 and the same letters of reference are used.

What we claim is:—

- 5 1. In a bolt small arm, the combination of a striker, a safety device free to turn about a longitudinal axis, a sight carried by the safety device, and means carried by the safety device which prevent the striker from moving forward when the safety device is in one horizontal position but allows the striker to act when the safety device is in a vertical position.
- 10 2. In a bolt small arm, the combination of a striker, a safety device free to turn about

a longitudinal axis, a sight carried by the safety device, and means carried by the safety device which prevent the striker from moving forward when the safety device is in one horizontal position but allows the striker to act when the safety device is in a vertical position and also when it is in the other horizontal position.

HENRY WILLIAM HOLLAND.
WILLIAM MANSFIELD.
